STAGE CONSTRUCTION FOR THEATERS
AND THE LIKE

Graeme E. Young, Deerfield, Ill.

Application May 22, 1937, Serial No. 144,245

6 Claims. (Cl. 20—1.123)

This invention relates to improvements in stage construction particularly adapted, though not limited in its use in theaters, for television, and other purposes, and one of the objects of the same is to provide an improved stage construction embodying a plurality or series of sections, each section being adjustable with respect to the other, and associated with each of the sections is a rotatable platform or table. The sections are adapted to be shifted or bodily moved with relation to each other, and each of the platforms or tables are adapted to be rotated with relation to its respective supporting section, and also with relation to the other platforms or tables and upon which sections, as well as rotatable platforms or tables, may be arranged suitable stage settings, each being operable to facilitate change in scenes or stage settings.

A further object is to provide a stage of this character in which the sections are angular in cross-section whereby when the sections are properly positioned with respect to each other, they will not only provide a substantially continuous or uninterrupted surface, but a considerable area will be provided for the stage settings, within a minimum area, and the sections are so arranged that as large a stage area as may be desired, within the limits of the structure, may be employed.

A further object is to provide in a stage of this character means whereby the sections may be bodily adjusted or shifted to positions out of contacting relation to and with the other sections, then rotated to present another section of scenery, after which the sections are moved back into co-operative relation to form or present the assembled stage relationship.

A further object is to provide an improved stage structure of this character which will be of a simple and compact construction, easily manipulated, and effective and efficient in operation.

To the attainment of these ends and the accomplishment of other new and useful objects as will appear, the invention consists in the features of novelty in substantially the construction, combination and arrangement of the several parts, hereinafter more fully described and claimed and shown in the accompanying drawing illustrating this invention, and in which

Figure 1 is a top plan view of a stage of this character constructed in accordance with the principles of this invention, partly broken away and showing in dotted lines another position in which some of the parts may be moved.

Figure 2 is a view similar to Figure 1 of a por-

tion of a stage structure showing the manner of adjusting one of the sections with relation to others of the sections.

Figure 3 is a detail sectional view, on an enlarged scale, taken on line 3—3, Figure 1.

Figure 4 is a vertical sectional view taken on line 4—4, Figure 1.

The stage consists essentially of a plurality of sections 19 of any desired size, construction and configuration, but in the present exemplification of the invention they are shown as being preferably hexagonal in cross-section.

Each of these sections consists essentially of a body portion having supporting surfaces 11 and is mounted upon a carriage 12, also of any desired or suitable construction. The section 11 may be supported by the carriage in any suitable manner so as to rotate about the vertical axis. A simple and efficient manner of supporting the section upon the carriage is by means of ball or roller bearings 13 operating in suitable raceways.

The carriage itself may be supported by means of caster wheels 14 that run in tracks or ways 15 having suitable stops 16—17 at the extremities thereof so that when the carriage 12 is bodily moved the rollers will run upon the tracks 15 and the carriage will be limited in its movement by the stops 16 and 17.

Supported by the section 11 is a platform or table 18 which is mounted for rotation with respect to the section in any suitable manner and about an upright axis.

A simple and efficient means for so mounting the table or platform are balls or roller bearings 19 which operate in suitable raceways.

The table or platform 18 may be of any desired diameter and may be located with its axis concentric with the axis of the section 11 or eccentric with respect thereto, and the table or platform may be located in any desired position with respect to the section upon which it is mounted.

The upper surface of the table or platform 18 is preferably flush with the upper surface of the section 11.

Any number of these sections 11 may be employed and they are arranged in abutting relation so that a substantial portion of the periphery of the sections will abut a substantial portion of the periphery of the next adjacent section or 50 sections.

These abutting portions of the peripheries of these sections maintain them against rotation about their vertical axes with respect to their supporting sections.

The sections 10, as shown, being hexagonal in cross-section, one of the faces of each section will abut one of the faces of the next adjacent section. The sections 10 may be arranged about a 5 central platform or table 20 which latter may also be of any desired construction and of any desirable configuration in cross-section.

As shown, the central platform is hexagonal in cross-section and is stationary or non-rotatable and is encompassed by the sections 10.

The sections 10 are mounted with respect to the central platform 20 so as to be bodily adjustable toward and away from the latter and radially with respect thereto, the upper surface of 15 the platform 20 being substantially flush with the upper surface of the sections 10 and the tables 18.

When the parts are in the assembled position as shown in full lines in Figure 1, the abutting 20 surfaces of the sections with respect to the platform 20, will maintain the sections 10 locked or against rotation about their vertical axes and in this position any suitable stage setting or 25 scenery may be placed upon the sections and platforms, or if the stage is employed for television, the televiser may be mounted upon the platform 20 and if it is desired to employ a larger area of the stage construction than can be employed when the televiser is mounted upon the platform 20, it may be moved to any position and 30 upon any of the sections or tables or platforms to command a greater area of the stage.

The scenery to be used in the instant case is arranged or erected when the sections are as 35 shown in full lines in Figure 1.

At the same time additional scenes or sections of scenery may be placed upon the sections 10, as well as the tables 18, so that when the sections 10 are shifted or the tables 18 rotated, or both, 40 they will be brought into view in conjunction with or in place of the scenes which would be employed with the parts in position as shown in full lines in Figure 1, or co-operate with each other to form new scenes or stage settings after 45 the previously arranged scenes have been moved out of position for use.

This change or shifting is effected by moving the carriage 12 from the full line position shown in Figure 1 to the dotted line position, thereby 50 moving the contacting portions of the peripheries of adjacent sections out of engagement. This will permit the section 10 to be swung about its vertical or upright axis as shown more clearly in Figure 2 to position any predetermined portion of the section with respect to the other sections.

The section is then moved back into the full line position shown in Figure 1 so as to co-operate with the other sections and so that it will be maintained against rotation.

Obviously any form of mechanism may be employed, necessary or desirable for the purpose, to rotate the various sections and tables.

In the present exemplification of the invention, however, the structure is so designed that the various parts may be adjusted or rotated manually.

While the preferred form of the invention has been herein shown and described, it is to be understood that various changes may be made in 70 the details of construction and in the combination and arrangement of the several parts, within the scope of the claims without departing from the spirit of the invention.

What is claimed as new is:—

75 1. A stage of the character described embody-

ing a stationary platform, a plurality of sections angular in cross-section encompassing said platform and arranged in side by side relation, extended portions of the peripheries of each of said sections abutting the periphery of said platform, 5 other extended portions of the peripheries of the sections abutting the peripheries of the next adjacent sections, said sections when in assembled relation forming a substantially uninterrupted supporting surface about said platform, means 10 mounting said sections for bodily adjustment with respect to each other and radially towards and away from said stationary platform, and out of and back again into side by side contacting relation with each other, means for limiting such 15 radial adjustment and for maintaining said sections in fixed relation with respect to each other, and means also mounting said sections for rotation about vertical axes when the sections are out of contacting side by side relation, whereby 20 to position the moved section in a different side by side relation to an adjoining section.

2. A stage of the character described embodying a stationary platform, a plurality of sections angular in cross-section encompassing said platform and arranged in side by side relation, 25 extended portions of the peripheries of each of said sections abutting the periphery of said platform, other extended portions of the peripheries of the sections abutting the peripheries of the 30 next adjacent sections, said sections when in assembled relation forming a substantially uninterrupted supporting surface about said platform, means mounting said sections for bodily adjustment with respect to each other and radially towards and away from said stationary 35 platform, and out of side by side relation and back again into contact with each other, means for limiting such radial adjustment and for maintaining said sections in fixed relation with 40 respect to each other, means also mounting said sections for rotation about vertical axes when the sections are out of side by side relation, whereby to position the moved section in a different side by side relation to an adjoining section, and a 45 platform or table of substantial diameter revolvably mounted upon each of said sections.

3. A stage of the character described embodying a stationary platform provided with a plurality of peripheral faces, a plurality of sections 50 encompassing said platform and being arranged in side by side relation with respect to each other, said sections having abutting faces, each of the said faces of said sections also adapted to be brought into abutting relation with the said faces of said platform, means affording a bodily relative movement of said sections one toward and away from the other and out of side by side relation, and also toward and away from the platform whereby any predetermined one or more of 55 said sections may, when moved away from each other and also from the platform, be rotated about its axis to position other faces of its periphery to be moved into different side by side relation, and also abutting relation to the platform, means for limiting the movement of the said sections radially away from the stationary platform and for maintaining the sections in fixed 60 positions with relation to each other, the said sections at all times in assembled relation providing 65 a substantially uninterrupted supporting surface of substantial radial depth about said platform.

4. A stage of the character described embodying a platform, a plurality of hexagonal spaced sections, said sections arranged in side by side 75

relation and encompassing said platform with the proximate faces of adjacent sections abutting, thereby providing a substantially uninterrupted supporting surface encompassing said platform, means affording a bodily radial movement of said sections one toward and away from the other and out of side by side relation whereby any predetermined one or more of said sections may, when moved away from each other and out of side by side relation, be rotated about its axis to position other faces of its periphery to be moved into different side by side abutting relation to the proximate face of the next adjacent section, all of the abutting faces of the sections and of the platform being of substantially equal areas, stop means for limiting such radial movement of the sections away from the platform and for maintaining the sections in fixed positions with relation to each other, and a platform or table of substantial diameter revolvably mounted upon one or more said sections.

5. A stage of the character described embodying a platform provided with a plurality of peripheral faces arranged at angles to each other, 25 a plurality of sections, each of said sections provided with a plurality of angularly disposed peripheral faces, said sections arranged in side by side relation and encompassing said platform with the proximate faces of adjacent sections 30 abutting and the proximate faces of the platform and of the sections also abutting, thereby providing a substantially uninterrupted supporting surface with and also encompassing said platform, means affording a radial bodily relative movement of said sections one toward and away

from the other and out of side by side relation, whereby any predetermined one or more of said sections may, when moved away from each other and from the platform, and out of side by side relation, be rotated about its axis to position other faces of its periphery to be moved into a different side by side abutting relation to the proximate face of the next adjacent section and of the platform, a supporting surface on which said sections are movable, and stops co-operating with said surface to limit such radial movement.

6. A stage of the character described embodying a platform, a plurality of sections, each of said sections provided with a plurality of peripheral faces disposed at an angle with respect to each other, said sections arranged in side by side relation and encompassing said platform with the proximate faces of adjacent faces abutting, thereby providing a substantially uninterrupted supporting surface encompassing said platform, 20 means affording a radial bodily relative movement of said sections one toward and away from the other and out of side by side relation whereby any predetermined one or more of said sections may, when moved away from each other and out of side by side relation, be rotated about its axis to position other faces of its periphery to be moved into different side by side abutting relation to the proximate face of the next adjacent section, said sections being movable upon ways, 30 and stop devices co-operating with said ways whereby to limit such radial movement of said sections and for maintaining them in fixed assembled relation.
